UNITED STATES PATENT OFFICE.

THOMAS HOLDER, OF EDINBURGH, SCOTLAND.

NEEDLE-THREADER.

SPECIFICATION forming part of Letters Patent No. 734,709, dated July 28, 1903.

Application filed June 14, 1902. Serial No. 111,791. (No model.)

To all whom it may concern:

Be it known that I, THOMAS HOLDER, a subject of the King of Great Britain, residing at Edinburgh, Scotland, have invented certain new and useful Improvements in Needle-Threaders, of which the following is a specification.

This invention relates to an appliance for threading needles which can be used without sight by the mere feel of the fingers.

In the accompanying drawings, Figures 1 and 2 show my appliance for threading needles.

It consists of a short bar A, preferably of metal, with a hole B bored a certain depth in its end to receive the head of a needle C, and a cross-hole D in such a position as to be in line with the eye of the needle when it is inserted in the end hole. As most needles have their eyes in very nearly the same position in their heads, the cross-hole D is in proper position for almost all ordinary needles, except such as are of extra dimensions. Through the cross-hole passes a wire E, having a hook H at its end, somewhat like that of a crochet-needle, this wire being attached to and projecting from an arm L, which is attached at its upper end to the side of the bar A, but is movably held away from the bar by a spring F. At the lower end of the bar A is an A-shaped slit M, one side of which is parallel with the edge of the bar.

This appliance is operated in the following manner: The head of the needle is inserted in the end hole B, and the hooked wire or fin-

ger E is pushed through and beyond the needle's eye by pressing on the arm L, which carries it. The thread is then passed into the slit M, so that it rests against the finger E. On relieving the arm L from pressure it springs 40 away along with the hooked wire which draws the loop of the thread through the eye of the needle, thus threading it, so that it can be withdrawn along with the thread.

The appliance, suitably modified, can be 45 used for threading the needle of a sewing-machine. In this case the hole to receive the needle is of greater depth and is transverse to the rod and has a lateral slit for the escape of the engaged thread.

What I claim is—

A needle-threader comprising a bar with an A-shaped recess in its lower end, one side of said recess being parallel with one edge of said bar, a transverse aperture through the 55 edge of said bar terminating at the recess, and an aperture in the lower end of the bar for the needle, said aperture terminating at the transverse aperture, in combination with a spring-actuated arm hinged to the upper 60 end of the bar, and provided with a hooked finger which is adapted to pass into the transverse aperture, as herein set forth.

In testimony whereof I have hereunto set my hand in the presence of two subscribing 65 witnesses.

THOMAS HOLDER. [L. S.]
